UNITED STATES PATENT OFFICE

114,548

DESIGN FOR A TOY GUN

Albert T. Linney, Lexington, Ky.

Application September 7, 1938, Serial No. 79,765

Term of patent 7 years

To all whom it may concern:

Be it known that I, Albert T. Linney, a citizen of the United States, residing at Lexington, in the county of Fayette and State of Kentucky, have invented a new, original, and ornamental Design for a Toy Gun, of which the following is a specification, reference being had to the accompanying drawing, forming a part thereof.

In the drawing:

I claim:

The ornamental design for a toy gun, as shown.

ALBERT T. LINNEY.
